United States Patent Office.

STEPHEN T. PEARCE, OF NEW YORK, N. Y.

Letters Patent No. 80,763, dated August 4, 1868.

IMPROVED MACHINE FOR SEPARATING ORES AND OTHER MATERIALS.

The Schedule referred to in these Letters Patent and making part of the same.

TO ALL WHOM IT MAY CONCERN:

Be it known that I, STEPHEN T. PEARCE, of the city, county, and State of New York, have invented a new and improved Machine for Separating Ores; and I do hereby declare that the following is a full, clear, and exact description thereof, which will enable others skilled in the art to make and use the same, reference being had to the accompanying drawings, forming a part of this specification.

The object of this invention is to provide an improved machine for separating finely-pulverized ore, sand, and other substances by the combined action of centrifugal force and frictional contact.

It consists of an arrangement of means whereby the granulated and sized substance to be acted upon, being discharged upon the surface of a cone of polished metal under rotary motion upon its vertical axis, will be set into motion by the contact of the same with the cone, and discharged therefrom in various lines, governed by the specific gravity of the particles and the frictional quality of the same, in a manner to fall into various receptacles arranged with reference to the various positions in which the particles will fall to separate them in the order of their falling.

Figure 1 represents a sectional elevation of my improved apparatus, taken on the line $z z$ of fig. 2; and

Figure 2 represents a horizontal section of the same, taken on the line $y y$ of fig. 1.

Similar letters of reference indicate corresponding parts.

A represents a cone, which may be made of any suitable material susceptible of being highly polished, which is suspended on a vertical shaft, B, arranged in any suitable framing, and provided with means for giving it rotation.

C represents a spout, for conveying the material to be separated to the surface of the cone, near the top, and preferably at one side of the radial line of the said cone.

D represents a receptacle for the ore or other substance, which is divided into compartments, $a a' a'' a'''$, and $d d' d'' d'''$, having spouts communicating with other receptacles, or with elevators, for conveying the ore back to the spout C, or to other separating-apparatus.

Supposing the sand or fine ore, which has been previously sized by sifting or otherwise, to be discharged in a fine jet through the tube C upon the cone, at the point e , while the same is in a state of rotary motion, those particles having the greatest specific gravity and the least frictional quality will be first discharged from the surface of the cone, and fall into the compartment a , while those having, say, about the same weight, but more frictional quality, will be discharged into the compartment d , and, again, those having a less weight and frictional quality, would be discharged into the compartment a' , and so on, in the same order, the whole will be distributed according to their qualities of weight and friction, which may be determined for the different grades by the receptacles into which they fall.

The form of the cone may be varied as desired, by making the inclination more or less abrupt, or making the surface concave or convex.

The sizing may, if preferred, be done after the particles have been submitted to the action of the separator, in which case it will be found that small particles, of high specific gravity, and large particles, of low specific gravity, will fall together, which may be separated by sifting.

This improved machine may be used with excellent results in a vacuum for separating such fine particles as would in the open atmosphere be taken up by it and carried away.

It may also be used with advantage in separating grain and other articles.

Having thus described my invention, I claim as new, and desire to secure by Letters Patent—

1. A mechanism, arranged to separate the particles of pulverized ore or other granular substance, by impelling it, by the joint action of gravity and centrifugal force, over a metallic or other polished surface, which will modify, by the frictional contact of the same, the direction imparted to the particles of such substance, substantially as and for the purpose set forth.

2. The combination, with the rotating cone A, of the receptacle D, divided into compartments, substantially as and for the purpose described.

The above specification of my invention signed by me, this 15th day of July, 1868.

S. T. PEARCE.
